UNITED STATES PATENT OFFICE.

ERNEST O. CARTWRIGHT, OF SPRINGFIELD, OHIO, ASSIGNOR TO CHARLES F. GARDNER,
OF SPRINGFIELD, OHIO.

INJECTOR OR EJECTOR.

1,341,010.

Specification of Letters Patent.

Patented May 25, 1920.

Application filed March 7, 1919. Serial No. 281,272.

To all whom it may concern:

Be it known that I, ERNEST O. CARTWRIGHT, a citizen of the United States, residing at Springfield, in the county of Clark and State of Ohio, have invented certain new and useful Improvements in Injectors or Ejectors, of which the following is a specification.

My present invention has for its object 10 to provide an improved device for ejecting liquids and solids from sumps, wells or other places and injecting the same into a separate tank. All devices of this nature with which I am familiar create a partial vacuum 15 in the suction chamber or passage by applying the motive liquid or gas under pressure through an opening or nozzle either in the center or at one side of the vacuum chamber; by reason of this construction the 20 entry of the suction passage into the vacuum chamber, in the case of a central jet, is restricted to a location at one side of the chamber, with a consequent deflection or diffusion of the suction column before it 25 joins the discharge column; or in case the pressure jet is made to enter the chamber at one side there is also a deflection of the suction column to the side of the chamber opposite the entrance of the jet. These 30 deflections and diffusions are not apparent when liquid alone is being drawn up through the suction, and only slightly noticeable when liquid containing solids of comparatively slight bulk is being elevated, 35 but when the suction is required to handle masses containing solids of relatively large dimensions, in such a case with either of the jets last mentioned, the movement of the suction column is arrested at the junction 40 with the discharging column to the extent of breaking down the suction. My invention has for one of its objects to provide a device which is constructed in such manner that the material in the suction duct is 45 immediately enveloped in the discharge column as it rushes up to fill the partial vacuum created by the passage of the motive fluid into the discharge column whereby there is no deflection or diffusion of the 50 suction column because of the straight passage into the discharge chamber, and there is also no arrest of the mass in the suction column, due to the enveloping action of the pressure liquid.

55 Another novel feature of the present in-

vention is the provision for the renewal of the parts subjected to abrasion.

In its more specific nature, the invention includes those novel features of construction, combination and arrangement of parts, 60 all of which will be first fully described, then be specifically pointed out in the appended claims and illustrated in the accompanying drawings, in which:

Figure 1 is a detail side elevation of a 65 portion of a portable pumping apparatus for which my invention has been especially designed.

Fig. 2 is a vertical section of the same taken through the device which constitutes 70 my present invention.

Fig. 3 is an enlarged vertical section of a modification of the invention.

Fig. 4 is a horizontal section on the line 4—4 of Fig. 3, looking in the direction of 75 the arrow.

Fig. 5 is a vertical section of the perforated disk shown in Fig. 3.

Fig. 6 is a top plan view of the disk shown in Fig. 4.

Fig. 7 is a top plan view of a modified 80 form of disk.

Fig. 8 is a cross section of the disk shown in Fig. 7.

Fig. 9 is a plan view.

Fig. 10 is a cross section of the same showing substantially the type of disk disclosed in Fig. 2.

In the drawings; in which like letters and numerals of reference indicate like parts in 90 all of the figures, 1 represents the ejector housing which is provided with an extension 2 having a flange 22 adapted to be bolted, or otherwise secured to the source of motive fluid and the extension 2 incloses 95 a pressure chamber 3 which communicates with the pressure chamber 5 in the body 1 through a passage 6 that is controlled by a valve 15 operated by a hand wheel 16 or in any other suitable manner. 7 designates 100 a boss which is bored to receive the bushing 8, the bushing 8 having its upper outer portion tapered to seat in the central opening of a disk 13.

9 designates the suction pipe or nipple 105 through which the material from the source is drawn up and ejected into the duct or passage 10 by the fluid under pressure which passes through the passageways 13^a of the disk 13.

The duct 10 is flanged at 11 to fit the flange 4 of the body 1 to which it is secured in the usual manner, and it is recessed at 12 to receive the disk 13. When 5 the disk 13 is of the construction shown in Figs. 3 to 8, inclusive, it is not necessary to have the disk 13 threaded into the recess 12 since its engagement with the bushing 8 and the recess 12 will hold the disk 10 in place as well as hold the bushing 8 in the boss 7, the bushing in this construction need not be threaded into the boss. When the disk 13 is constructed as shown in Figs. 2, 9 and 10, however, it is preferable 15 either to force the disk into the recess 12 with retaining friction, or to thread it at 13^d and tap it into the recess. In that case also, the bushing 8 may be tapped into the boss 7, if found desirable.

20 The ring 13 has suitable passages 13^a either formed as a series of holes leaving a central annular seat portion 13^b or a series of cutaway portions leaving projections 13^c (see Figs. 7 and 8) to engage the bushing 8, or it may be formed in the shape of a ring (see Figs. 1, 9 and 10) having a passage 13^e spaced from the bushing 8 to form a solid or unbroken hollow column of motive fluid as such fluid is forced from the 30 chamber 5.

14 is a tapped opening from the pressure chamber 3 to which a suitable distributing union, through which the fluid under pressure may be delivered to hose pipes, may be attached, see for example my copending application Serial No. 280,976 filed on Mar. 6, 1919.

This invention is adapted for use generally in many environments, although I have 40 designed it especially for use in connection with a portable pumping apparatus forming the subject matter of my application aforesaid, and when so used the duct 10 connects with the tank duct 21 to deliver the material (solids and liquid) into the solids compartment 19 of the tank 25 from which the fluid content passes through the screen partition 20 into the liquid compartment 18 from whence it is drawn through the duct 50 23 and connection 24 into the centrifugal pump 17 from which it is delivered into the pressure chamber 3 to act as motive fluid in drawing up additional material through the suction duct 9.

55 It will be observed that with the present construction the pressure fluid, where it passes into the entrance of the duct 10, is in the form of a hollow cone, the apex of which is directed upwardly, thus causing 60 the formation of a partial vacuum at the upper end of the bushing 8, causing suction in the bushing passage and duct 9, thereby bringing up the material which it is desired to elevate and inclosing it in the surrounding envelop formed by the motive fluid col-

umn and forcing the material through the duct 10 and duct 21 into the proper compartment of the tank.

When the bushing 8 and disk 13 become worn they can be readily replaced by the 70 uncoupling of the parts 11 and 4, thus providing for the convenient renewal of those parts subject to abrasion.

From the foregoing description taken in connection with the accompanying drawings 75 it is thought the complete construction, operation and advantages of my invention will be readily clear to those skilled in the art and while I have especially designed the invention for use in connection with the portable pumping apparatus referred to yet I 80 desire it understood that I do not limit the use of my invention thereto as the same may be employed wherever found suitable.

What I claim is:—

1. In a device of the character described, a body having a relatively large pressure chamber, a suction duct passing through said chamber, a duct into which said suction duct discharges, means for delivering 90 liquid from said pressure chamber into said discharge duct around the outlet of said suction duct in the form of a surrounding envelop whereby a fluid envelop will be interposed between the sucked up material and 95 the walls of the discharge duct, substantially as shown and described.

2. In a device of the class described, a body having a receiving chamber and a pressure chamber with which said receiving 10 chamber communicates through a valved passage, a discharge duct, said body having a seat, a bushing held in said seat and projected through said pressure chamber and arranged to deliver into said discharge duct, 10 a duct connected with the receiving end of said bushing, said discharge duct being removably secured to said body and having a recess, a ring having a water pass seated in said recess and surrounding the exit end of 11 said bushing.

3. In a device of the class described, a body having a receiving chamber and a pressure chamber with which said receiving 11 chamber communicates through a valved passage, a discharge duct, said body having a seat, a bushing held in said seat and projected through said pressure chamber and arranged to deliver into said discharge duct, a duct connected with the receiving end of 12 said bushing, said discharge duct being removably secured to said body and having a recess, a ring having a water pass seated in said recess and surrounding the exit end of 13 said bushing, and said ring having provisions for engaging said bushing whereby the ring and bushing will be held in place.

4. In a device of the character described, a body having a receiving chamber and a pressure chamber and a valved passage be- 14

tween said chambers, said body having an outlet opening and also having a seat provided with a bore, a bushing held in said seat bore and projecting beyond the outlet 5 of said body, a cap member fitted on said body over the outlet thereof and having a chambered portion into which said bushing projects and having a discharge duct de-

livering from said chambered portion, and a ring member located in said chambered portion of said cap member and coöperating with the discharge end of said bushing to direct the pressure fluid in the form of an inverted cone envelop to said discharge duct.

ERNEST O. CARTWRIGHT.
